UNITED STATES PATENT OFFICE.

MILLER REESE HUTCHISON, JR., OF LLEWELLYN PARK, WEST ORANGE, NEW JERSEY,
ASSIGNOR, BY MESNE ASSIGNMENTS, TO ACOUSTIC PRODUCTS COMPANY, OF NEW
YORK, N. Y., A CORPORATION OF DELAWARE.

LOUD-SPEAKER.

Application filed June 12, 1926. Serial No. 116,855.

The present invention relates to means for transmuting energy impulses into audible sounds and further improvements in acoustic devices in relation to sound reproducing instruments or loud speakers, and has for one of its objects through a novel combination of parts and scientific principles, to produce superior results throughout the entire musical spectrum or scale.

10 It is also an object of my present invention to construct a highly compact and comparatively inexpensive, yet hardy instrument with beauty and truth of tones and overtones, and with increased power and volume 15 of sound throughout a wide range of frequencies.

With the above objects and certain other objects also in view which will become apparent as the present description proceeds, and 20 the drawings are studied, my invention consists in the novel parts and combination of parts, all as hereinafter will be more fully described and particularly pointed out in the claims.

25 Referring to the accompanying drawings forming a part of this specification in which like numerals designate like parts in all the views:

Figure 1 is a diagrammatic face view of 30 one of the plates or discs which form a part of my air confining structure.

Figure 2 is a side view in elevation of two 35 of these plates or discs assembled with a spacing between, shown in a horizontal position.

Figure 3 is a side view in section of two 40 of these plates or discs assembled with a spacing between, shown in vertical position and associated with a telephone receiver system partially in section and partially in elevation. The full diameters of the plates or discs are not shown, the peripheries being cut away in the view by broken lines.

Figure 4 is a side view of two of these 45 plates or discs with a spacing between, shown in vertical position in elevation, and associated with a pair of telephone receiver systems indicated in elevation. The full diameters of the plates or discs are not shown, the peripheries being cut away in the view by broken lines.

With further reference to Figure 1, 10, is 50 a plate or disc of metal or other suitable material, wood, hard rubber, bakelite or other

plastic material, for example, 11 is an 55 opening eccentric to the center of the plate or disc. 12, 12, 12, 12, 12, are the edges of partitioning members, and these partitioning members may be of metal or other suitable material, attached and held fast in position through grooves cut or moulded in the disc 10, or through soldering, cementing or any other suitable manner, or be cast or be moulded as an integral part of one or both of the discs 10, or be stamped up and drawn 60 by suitable dies to form mutually embracing or nesting flat horns.

It may now be seen that these partitioning members 12, 12, 12, 12, etc. shown curved in the present view, confine air volumes when 70 they are associated with a pair of spaced plates or discs, and these confined air volumes increase systematically in length from the central or common opening 11 to the outer periphery. Whereas in the present view 75 I have shown these partitioning members curved according to one mathematical development, it is evident that I may select other curves, or even straight lines for the partitioning members. For best results I 80 find that curved partitioning members give longer "horns" of progressive lengths and consequently longer columns of confined air of progressive lengths for resonance.

From a study of this design it is apparent 85 that my present new structure provides a series of exceedingly compactly associated horns of various lengths, from very short ones to comparatively very long ones, and therefore I secure very widely differing 90 resonance characteristics.

To be specific in the identification of some 95 of my curved horns 13, 14, and 15, are the small ends of three of them mutually terminating within the common eccentric center of sound propagation 11, and the respective large ends of the horns terminating at the periphery of the plates or discs 13'-14' and 15' and enclosing the curved air columns 16, 17 and 18.

By tracing the passageway from the common opening 11 of the resonating "horns" 13-13' and 14-14' and 15-15' it will be appreciated what long columns of resonating air are secured, and how compactly I am enabled to nest them, and how cheaply I may construct them.

With further reference to Figure 2, 10, 10,

are the discs or plates, 11, is the eccentrically positioned opening as indicated by the dotted lines 19, and 20, and 12, 12, 12, 12, are the partitioning members.

5 With further reference to Figure 3, 10, 10, are the discs or plates, 12, 12, 12, 12, are the partitioning members, either attached separately or integral members of the discs or plates, one or both of them as previously 10 pointed out, and 11 is the eccentrically located opening. A small disc 21, or an integral part of the large disc 10, such as a boss for example, closes the opening at the right hand side of the figure when only one sound 15 emitting device is employed, and a threaded boss 22, attached to or integral with the disc 10, engages the threaded member 23 of the telephone casing 24, containing the pole piece 25, the insulated wire 26, terminating in the connection ends 27 and 28. A 20 diaphragm 30 is held in position in a customary and standard manner in front of the pole piece 25, and in communication with the open throatway 31, which leads to 25 the eccentric opening, or center of sound propagation 11.

I have shown a simplified diagrammatic telephone receiver here in the interests of clearness, but I wish it to be clearly understood that I would use a standard design of 30 telephone receiver here with customary hardened steel permanent magnets, soft iron pole pieces, many turns of fine insulated wire upon said pole pieces, a ring washer on 35 one or both sides of the diaphragm, and such other features common to telephone receiver practice as are essential to high efficiency operation when associated with radio reception systems.

40 With further reference to Figure 4, where I have shown duplex opposed co-operating telephone receivers in elevation, 10, 10, are the plates or discs providing the side members of my air confining structure, 12, 12, 45 12, 12, are the end edges of the partitioning members, either attached or integral with the members 10, 10; and 22, is the boss of the telephone receiver on the left hand side of the drawing; 23, is the covering member 50 of the casing 24; and 27 and 28 are the connecting wires leading into the casing and a continuation of the winding of the instrument. 11 is the position of the eccentric opening, and the center of sound wave 55 propagation of both electro-magnetic diaphragm systems; 22' is the boss of the telephone receiver on the right hand side of the drawing; 23' is the casing member of the casing 24', and 27' and 28' are the connecting wires leading into the casing and a continuation of the winding of the instrument. In practice, I may connect the wires 60 27, 28, and 27', 28' in series or in parallel to the source of sound transmuting electrical impulses of a radio system.

With the duplex arrangement of electro-magnetic diaphragms it is clear that I may produce an instrument of great power, since the sound waves propagated simultaneously are delivered to the common center of my 70 compact nest of "horns" of various resonance characteristics. Diaphragms are capable of highly complex vibration, and in my present structure I provide a series of horns of a plurality of characteristics, in an 75 economic position for selective resonance. To place the matter more technically, I offer a series of air columns with progressive resonance characteristics, to the action of a diaphragm or diaphragms in highly efficient 80 combination.

Although I have not shown a sound reflector for backing up the instrument described, I may of course use one, or I may place such an instrument as described in a cabinet with 85 sound reflecting surfaces and thereby enhance the effects produced. Whereas I have shown the instrument in vertical position, there are conditions under which I may prefer to operate the instrument in a horizontal 90 position. Whereas I have shown my flat horns of progressing length closely nested through our design of construction, I may resort to the construction of a multiplicity 95 of separate units adapted to closely nest and form thereby the sounding element of my loud speaker. Whereas I have illustrated and described telephone receivers as my sound emitting devices, I do not confine myself to such systems, as I may use a musical 100 arc, or a speaking arc as sound emitting devices, or any other suitable sound emitting contrivance.

Having described my invention, I claim:

1. A loud speaker of multiple resonance 105 characteristics comprising a pair of spaced plates one having an opening near the center, a plurality of walls connecting said plates, said walls being curved in length and extending between the edge of said 110 hole and the edges of said plates, said walls being of different lengths to provide a plurality of externally related air columns of different lengths, and an electromagnetic diaphragm device connected to said opening. 115

2. A loud speaker of multiple resonance characteristics comprising a pair of spaced circular plates each having an opening off center, a plurality of walls connecting said plates, said walls being spirally curved in 120 length and extending between the edges of said holes and the edges of said plates, said walls being of different lengths to provide a plurality of externally related curved and nested air columns of different lengths, and sound emitting devices connected to said 125 holes.

3. Acoustic apparatus comprising a pair of spaced plates, a plurality of walls connecting said plates said walls being curved 130

in length to provide a plurality of externally related air columns, and an energy transfer device in operative relation to said air columns.

5. Acoustic apparatus having multiple resonance characteristics comprising a pair of spaced plates, a plurality of walls connecting said plates, said walls being curved in length and extending between the inner portion of said plates and the outer edges thereof, said walls being of different lengths to provide a plurality of externally related air columns of different lengths, and an energy transfer device associated with the inner ends of said air columns.

10. Acoustic apparatus having multiple

resonance characteristics comprising a pair of spaced plates, a plurality of walls connecting said plates, said walls being spirally curved in length and extending between the inner portion of said plates and the outer edges thereof, said walls being of different lengths to provide a plurality of externally related air columns of different lengths, and a common energy transfer device connected to said air columns at the inner portion of said plates.

15. Signed at East Orange, in the county of Essex and State of New Jersey, this 7th day of June, A. D. 1926.

MILLER REESE HUTCHISON, JR.
